(57) **CLAIM**

I claim the ornamental design for a toy vehicle, as shown and described.

DESCRIPTION

FIG. 1 is a side view of a toy vehicle according to an embodiment of the present disclosure. The opposing side of the toy vehicle is a mirror image of FIG. 1.

FIG. 2 is a top view of the vehicle of FIG. 1.

FIG. 3 is a front view of the vehicle of FIG. 1; and, FIG. 4 is a rear view of the vehicle of FIG. 1.

The broken or dashed lines shown in the drawings are for illustrative purposes only and form no part of the claimed design.

The shading lines shown in the drawings represent the three-dimensional contour of the design, and are not intended to indicate surface decoration.
